LOAD-CARRYING MEMBER

Michael Watter, Philadelphia, Pa., assignor to
 Edward G. Budd Manufacturing Company,
 Philadelphia, Pa., a corporation of Pennsylvania.

Application February 20, 1943, Serial No. 476,534

5 Claims. (Cl. 189—37)

The invention relates to a load-carrying member or girder, such as is particularly adapted for use as the rib of an airfoil; particularly where such rib is required to carry heavy loading.

It is among the objects of the invention to provide such a rib having a high strength-weight ratio, and which can be readily fabricated out of light gauge sheet metal, such as high-tensile stainless steel.

To accomplish these objects the rib structure is so designed as to permit certain of the strength members thereof, as the chords, while conforming generally to the curved contour of the airfoil in which the rib is to be used, to be made of parts of rectilinear form, in which form these parts can be readily made of the desired cross-section by simple draw-rolling of a strip of the sheet metal.

It is quite difficult to form angle or channel sections of stainless steel, for example, of the gauge required in such chords, so as to give the exact contour of the airfoil. It is desirable for maximum strength that the chords lie as close to the marginal contour as possible. The difficulty is avoided and the last-mentioned desirable feature is attained by the invention by making the chords in rectilinear sections joined at their meeting ends to form the full length chords.

A web plate or an extension thereof is used according to the invention to form the marginal cap strip contour forming portions of the rib. Between the chords the web plate is reinforced by a transversely corrugated sheet and for balance the chords are of composite construction, parts located on one side of the web and parts on the other. The chord elements located on the side of the web plate reinforced by the corrugations are further provided to prevent distortion of the ends of the corrugations under load, since these chord elements are secured to the corrugations and to the web plate, thus tying the parts strongly together. To facilitate assembling of these chord elements and to stiffen the chord structure still further one of these elements secured to the corrugations has a freely projecting portion, preferably for added stiffness, a flange portion projecting laterally of the web plate and secured to the web plate by a second element secured to the flange and the web plate and bridging the ends of the corrugations.

Other and further objects and advantages and the manner in which they are attained will become apparent from the following detailed description when read in connection with the drawings forming a part hereof.

In the drawings,

Fig. 1 is a chordwise sectional view through an airfoil showing the rib of the invention embodied therein,

Fig. 2 is a similar sectional view on an enlarged scale showing the nose end of the rib;

Fig. 3 is a sectional view of the nose portion of the rib taken substantially along the line 3—3 of Fig. 2;

Fig. 4 is an enlarged fragmentary perspective view, with parts broken away, of the lower portion of the rib showing the joint between abutting rectilinear chord sections, as seen looking in the direction indicated by the arrows at the end of the section line 4—4 of Fig. 1, and;

Fig. 5 is a vertical sectional view through the rib on substantially the same scale as Fig. 4, taken substantially along the line 5—5 of Fig. 1, part of the web being broken away.

In the embodiment of the invention selected for illustration the load-carrying member or girder is shown comprising a main strength rib 10 of an airfoil 10, such as the horizontal stabilizer of an aircraft, although it will be understood that the novel features thereof may be useful in other relations.

Referring to Fig. 1, the airfoil 10 is shown as having a convexly curved top and bottom and embodies a nose portion 11, an intermediate spar 12 and a rear spar 13, these parts being strongly interconnected by a strong rib, designated generally by 14, and other ribs spaced from the rib 14 and from each other, but not shown herein extend chordwise of the wing. A suitable trailing edge portion not shown is secured to the rear spar to complete the airfoil section.

The outer marginal contour of the rib 14 conforms generally to the curvature of the airfoil. In the nose portion, it extends outwardly to the skin, and the nose skin sheet, as 15, directly overlaps and is secured to the marginal portion of the rib in this region. Rearwardly of the nose, the marginal portions of the rib, while conforming generally to the contour of the airfoil, are inwardly offset to receive the reinforced skin blanket 16, 16', and to pass under the chords of the spars 12 and 13 and be secured thereto. In the region between the nose and the rear spar 13 the skin blanket comprises a skin sheet 16 stiffened by an inner reinforcing structure, designated generally by 16", to which are secured a series of clips, as 17 which, in turn, have their inner portions overlap the marginal portions of the rib, and are secured thereto in the overlap. The skin sheet 16 at the front is secured by a splice plate, see

55

Fig. 2, or otherwise to the skin sheet 15 of the nose portion and where it overlaps the chords of the spars it is further secured to them. Since the skin and spar arrangement does not form a part of this invention, further description thereof is believed unnecessary.

The main body of the rib 14 comprises a flat web plate 17 having its outer margin conforming generally to the contour of the airfoil. In the nose region, see Figs. 2 and 3, where the web plate extends substantially to the skin, its margin is reinforced by angles 18 and 19, the outer arms of which lie parallel to the skin sheet 15 and are interconnected to each other and to the skin sheet by an overlying flat strap 20.

Rearwardly of the nose portion the margins of the web plate 17 are formed by separate top and bottom cap strip extensions 21 and 22, see Fig. 5, flanged in their outer margins, as at 23 so as to give them greater strength and stiffness. As shown in Figs. 1 and 2, the forward ends of these extensions are outwardly offset to overlap both the nose web plate and the angular reinforcement, and are secured, as by spot welding, to both. These forward offset ends, as 21' and 22', may comprise separately formed pieces, as shown, overlapping and secured to the forward ends of the cap strip extensions 21 and 22.

As shown in Fig. 5, the cap strip extensions 21 and 22 have a wide overlap inwardly with the main body of the web plate 17 and are strongly secured thereto so as to form, in effect, an integral part of the web plate as a whole, by numerous spot welds in the overlap.

To give the web plate the characteristics of a strong load-carrying beam or girder, it is reinforced adjacent its top and bottom margins by chord members designated generally by 24 and 25. Between the chord members and to give the web plate great stiffness against buckling, it is reinforced by a vertically corrugated sheet or sheets 26 spot welded through the contiguous corrugations to the web plate 17. For convenience of manufacture, the corrugated sheet 26 may be built up in sections with vertical overlapping joints, as indicated at 27, in full lines in Fig. 4 and in dotted lines in Fig. 1. In the nose portion, see Fig. 3, the corrugated sheet extends outwardly close to the marginal angle 19 and the chord parts 33, 34 later to be described as being located on the corrugated side of the web, are discontinued through the nose portion.

The chords 24 and 25 are of composite construction for convenience of manufacture and, to provide a substantially balanced construction on opposite sides of the plane of symmetry of the web, parts of the chords are located on opposite sides of the web plate 17, as clearly appears in Figs. 4 and 5. The chord parts on each side of the web plate are preferably located close to the contoured margins of the web plate but since this would ordinarily require that they be bent to conform to the curvature of the airfoil a special construction is provided.

Since it is desired to manufacture them of angular or channel form sections for strength and stiffness, to so bend them, particularly when made of high-tensile stainless steel, would require difficult bending operations.

Accordingly, to avoid this bending, and still attain the advantage of having the chords as a whole conform nearly to the contour of the margins of the web and be located relatively close to said margins, the chords are preferably built up of rectilinear sections, having their ends secure-

ly joined together to form, in effect, a continuous chord member from end to end of the rib.

As shown in Fig. 1, the chord parts overlapping the flat side of the web plate 17 are each, both the top and bottom parts, built up of three rectilinear sections 28, 29 and 30. As shown, these sections consist of shallow outwardly facing channels strongly spot welded to the double thickness metal formed by the overlap of the body of the web plate 17 and its marginal extensions or cap strips 20, 21. The ends of the sections may abut, as shown, in the joint between sections 29, 30 shown in detail in Fig. 4, the abutting ends being overlapped by a junction strip 31 strongly welded to the adjacent ends of the sections. The joint may be additionally stiffened by an angle 32 welded to the junction strip 31. The junction strip, as 31, may be extended, as shown, through the entire length of the intermediate section 29, 20 and into overlapping engagement with the forward section 28, as shown, for example, at the top of Fig. 1.

All the joints between the sections may be made in this way or, as shown at 32' in Fig. 1, the joint may be made by cutting away the inside flange of one of the channel sections as 29, and stopping the strip 31 short of the end of channel 29 and lapping the bottom of the end of the channel section 28 directly over the bottom of the end of the channel 29 and spot welding them together in the overlap. Additional angle stiffeners, as 31, could also be applied, if desired, to this type of joint.

Certain of the chord parts on the opposite side of the rib are similarly constructed in rectilinear sections joined together at their ends. They flank the margins of the corrugated sheet reinforcement and are secured thereto and to the web plate 17. This securing of the chord parts to the margins of the corrugations prevents the distortion of the side walls of the corrugations under load and adds materially to the stiffness of the rib structure.

As shown in Figs. 4 and 5 the chord parts on this corrugated sheet side of the rib are preferably fabricated, for each the top and bottom chords 24 and 25, out of two longitudinally extending channel members 33 and 34. Channel member 33 is in rectilinear sections, and has one of its side walls as 35 arranged slightly beyond the margin of the corrugated sheet 26, and of widened construction and flanged in its margin. This member can readily be secured to the contiguous corrugations, after the corrugated sheet 26 has been spotwelded to the web plate 17, by inserting a spotwelding electrode through the ends of the corrugations.

After the member 33 is so secured in place it is further stiffened and rigidly tied to the web plate extensions 21, or 22, by the channel member 34 which has a wide side wall as 36, also flanged in its margin and directly welded to the adjacent plate extension and its bottom wall adjacent its shallow side wall in overlapping relation with and spotwelded to the side wall 35 of the member 33. The laterally projecting double thickness flange so produced adds materially to the stiffness of the chord and the entire rib structure. As indicated in Fig. 4, the longitudinal sections of the member 33 may be joined by lap strips 31 and angle reinforcements 32, in a manner similar to the joinder of the sections 29 and 30 of the chord parts on the opposite side of the rib. Channel member 34, because it is more readily bent by reason of its right angular rela-

tion, to the web plate of the rib, may be made continuous over the various longitudinal sections of member 33. Accordingly, no lap strips are required, or shown, in connection with this member. It is understood, however, if difficulty in bending it at the joints should be encountered, it may very well be constructed in longitudinal sections and joined in the manner indicated in connections with the sections 28, 29, 30 and 33.

At the extreme nose portion the channel sections 28 may have their bottom walls offset and overlapped over the marginal angle 18 and spot-welded thereto, as shown in Fig. 2. For greater strength in this nose region the top and bottom channel section portions 28 of the chords may be reinforced, as shown in Figs. 2 and 3, by a flanged channel reinforcement 37 spotwelded thereto.

From the foregoing detailed description, it will be seen that a very strong and rigid rib construction readily fabricated from sheet metal parts and readily joined by spotwelding has been provided. However, it will be understood that the specific construction described is merely by way of illustration and that changes and modifications would readily occur to those skilled in the art. Such changes and modifications are intended to fall within the scope of the appended claims.

What is claimed is:

1. An airfoil rib comprising a web plate having a marginal portion conforming to the curved contour of the airfoil, a vertically corrugated stiffener sheet secured to said web plate and terminating short of the marginal portion thereof, a composite chord member secured to the web plate and its corrugated reinforcement including an angular member extending longitudinally along a margin of the corrugated sheet and secured thereto, and having an arm projecting in a direction away from the web, and another longitudinally extending member secured to said arm and to the web plate.

2. A load-carrying member comprising a chord and a web plate having a marginal portion extending beyond the chord, the web plate inside said marginal portion being reinforced by a trans-

versely corrugated sheet secured thereto, the chord comprising an angular member extending longitudinally along a margin of the corrugated sheet and secured thereto, and having a freely projecting portion beyond the margin of said sheet and a second longitudinally extending member interconnecting said freely projecting portion and the web plate.

3. A load-carrying structure having a curved outer edge, as an airfoil rib, comprising in combination, a web having marginal cap-strip portions conforming to the curved outer edge contour, and chordal members adjacent each edge, each chordal member including a series of rectilinear pieces secured to the web and secured together at their juxtaposed ends adjacent the outer edge.

4. A load-carrying structure having a curvilinear outer edge, as an airfoil rib, comprising in combination, a plate web, a cap strip overlapping said plate web interiorly and conforming to the curvilinear contour at its outer edge, and a chordal member secured to the overlapping portion of the web and cap strip, said chordal member including a series of rectilinear elements secured together at their juxtaposed ends adjacent the outer edge.

5. A load-carrying structure having opposite curvilinear outer edges, as an airfoil rib, comprising in combination, a plate web, cap strips overlapping the plate web and secured thereto at their inner edges, the cap strips at their outer edges conforming to the required contour for carrying the load, a segmental chord secured to each cap strip adjacent its inner edge, the chord segments being rectilinear and spliced to adjacent segments, a corrugated strut sheet secured to the plate web opposite said cap strips and chords and occupying the zone of and between the chords, further segmental chords secured over the outside of the strut sheet at the ends and opposite the first chords, and chordal strips secured to said cap strips over the ends of said strut sheet, the chordal strips and the second said chords being secured together.

MICHAEL WATTER.
